UNITED STATES PATENT OFFICE

CHARLES T. HOWSON, OF SILVER CREEK, NEW YORK, ASSIGNOR TO WALTER M. BUCH-HOLTZ AND ALBERT B. CHAPMAN, OF SILVER CREEK, NEW YORK

GAS MIXER

Application filed October 13, 1924. Serial No. 743,303.

My invention relates to improvements in gas mixers, and more particularly to that type in which a mixing chamber is provided into which air and gas is led to be mixed therein.

The primary object of my invention is the provision of a gas mixer of this kind which is inexpensive, exceedingly simple, and in which a thorough commingling of air and gas is provided for within space.

Another object of my invention is to provide a gas mixer in which novel means is provided for regulating the admission of air according to the admission of gas so that the proper quantity of air will be provided for the gas to assure highest efficiency.

A further object of my invention is the provision of a gas mixer in which gas is economically mixed with air and delivered in proper proportions from the mixer.

A still further object of my invention is to provide a mixer having adjustable gas and air controlling-elements whereby the amount of gas admitted to the mixer and also the quantity of air for proper mixture with the gas, may be regulated.

With the above and other objects in view the invention consists in the novel features of construction and in the arrangement and combination of parts to be hereinafter described and more particularly pointed out in the subjoined claims.

In the drawings:—

Fig. 1 is a longitudinal section through the gas mixer with its fittings attached thereto.

Fig. 2 is a transverse section taken on line 2—2, Fig. 1.

Fig. 3 is a transverse section taken on line 3—3, Fig. 1.

Fig. 4 is a longitudinal section taken through the inlet end of the mixer and showing an adjustable air controlling-element therein.

Fig. 5 is a transverse section taken on line

5—5, Fig. 4, looking in the direction of the arrow crossing said line.

Fig. 6 is a longitudinal section through the inner end of the air-nozzle, showing the manner in which the air deflector thereof is attached thereto.

The mixer comprises a casing or body portion 7 having an air-nozzle 8 at one end and a reducer cap or concentrator 9 at its other end. The body portion or casing comprises an elongated cylindrical member or mixing chamber 10, a hollow head or enlargement 11 at one end thereof, and an external flange 12 at the other end. The enlargement or head-end of said casing serves as the inlet end thereof, while the flanged end thereof serves as the outlet end.

The reducer cap or concentrator 9 has an outstanding flange 13 through which and the flange 12 of the casing, bolts 14 are passed, said bolts serving to fasten said reducer cap or concentrator to the outlet end of said casing. The reducer cap or concentrator is gradually reduced in diameter from the flanged portion thereof toward its outer end and is provided with an axial boss 15 which is internally threaded and receives the threaded end of an outlet or mixture pipe 16.

The hollow head or enlargement 11 is formed by a wall 17 extending outwardly from the inlet end of the elongated cylinder or mixing chamber, a cylindrical wall 18, and an outer end wall 19 parallel with and spaced from the wall 17. The wall 19 has an axial threaded opening formed therein, and to assure an extended threaded portion at this point, said wall is provided with an inwardly-directed flange 20.

The air-nozzle 8 is threaded into the axial threaded opening formed through the end wall 19 and its flange 20, and the inner end of said nozzle extends a distance beyond the inner end of said flange. Said air-nozzle is reduced in diameter at its outer end, as at 90

21, and into this reduced portion an air inlet pipe 22 is threaded.

The circular threaded wall thus formed in the end wall 19 of the hollow head or enlargement 11 has an annular grease groove 23 formed therein, and from one point of this groove a grease duct 24 extends outwardly through the end wall 19. At its outer end, this duct is enlarged and threaded to receive the threaded end of a grease cup 25. By means of this cup, grease, thick oil, or a similar substance is forced through the duct 24 and into the groove 23, thus keeping the threads formed externally on the air-nozzle 8 lubricated so it can be easily adjusted longitudinally within the end wall 19 of the enlargement or head. The grease, oil, or other substance confined within the groove 23 renders the connection of the air-nozzle to the hollow head or enlargement air-tight.

The air inlet pipe 22 opens into the interior of the air-nozzle, which is cylindrical a distance inwardly from said pipe, as at 26. From this cylindrical portion the interior 25 of said air-nozzle is gradually enlarged toward its inner end by flaring the wall, as at 27, to a plane passing transversely through the air-nozzle near its inner extremity, and from this plane said inner wall is flared at a 30 slightly greater angle directly to the inner extremity of said nozzle, as at 28. The outer circumferential surface of said air-nozzle is beveled or tapered at the inner end thereof, as at 29, and this beveled or tapered portion 35 meets the inner internally-flared portion 28 with a sharp angle so that a sharp circular edge is provided at the inner extremity of said air-nozzle.

At the junction of the outstanding wall 17 with the cylindrical wall of the mixing chamber 11, an internal flange 30 is provided, part of said flange extending into the hollow head or enlargement 11. The inner surface of said flange is tapered inwardly from the hollow head or enlargement to conform to the externally-tapered inner portion at the inner end of the air-nozzle, which inner end said internal flange 30, or at least a part thereof, surrounds in spaced relation. The 45 annular space 31 thus formed between said internal flange and said air-nozzle serves as the gas inlet or passage for the mixing chamber.

It may here be stated that by reason of the 55 internal flange 30 extending into the hollow head or enlargement and the flange 20 extending inwardly from the outer wall 19 of said hollow head or enlargement, and owing to the fact that the air-nozzle extends inwardly beyond said last-mentioned flange, a substantially annular gas chamber 32 is formed in said hollow head or enlargement. Entering said chamber at one point is a gas inlet 60 pipe 33, said hollow head or enlargement be-

ing provided with a lateral boss 34 into which said gas inlet pipe is threaded.

It may here be noted that the internal flange 31 restricts the internal diameter of the mixing chamber at its inlet end, and this flange is spaced from the flange 20 extending inwardly from the outer wall 19 of said hollow head or enlargement, thus forming an annular space 35 between the two flanges which serves as a passage or connection between the annular gas chamber 32 and the annular gas inlet or passage 31. This passage or connection may, however, be considered a restricted or reduced portion of the annular gas chamber.

Mounted in the air-nozzle is an air-deflecting cone 36, which has its apex directed toward the air inlet pipe 22 and its base terminating at or near the plane of the inner end of said air-nozzle. This air deflecting 85 cone may be of any suitable construction, but in the drawings I have shown the same stamped or formed of sheet metal and the conical wall thereof is spaced from the surrounding wall of the air-nozzle to form an 90 annular flaring air-passage 37. The cone may be held centrally within the inner portion of the air-nozzle in any suitable manner, but in the drawings I have shown the same provided with arms 38 extending radially therefrom and bent over the externally beveled or tapered portion at the inner end of the air-nozzle, at which point they are soldered, or otherwise fastened.

In the illustration shown in the drawings, 100 the annular inwardly-tapered gas inlet or passage 31 and the annular inwardly-flaring air passage 37 are shown somewhat exaggerated, since in practice the walls of these passages are in closer relation than shown, but it 105 is believed that in order to make clear the action of the gas and air as they pass through these passages, exaggeration in dimensions of these passages is desirable for purposes of illustration.

It will be understood that the air-nozzle 8 is adjustable within the hollow head or enlargement 11, and for this purpose the reduced portion at the outer end thereof may be made square, hexagonal or given any other 115 suitable formation whereby a tool, such as a wrench or the like, can be conveniently applied for rotating said air-nozzle, either to the right or left, with a view of threading the same inwardly or outwardly, and as the 120 beveled or tapered external portion at the inner end of the air-nozzle is parallel with the inner wall of the internal flange 30, the threading of the air-nozzle inwardly to a greater degree than that shown in the drawing, will narrow or restrict the annular inwardly-flaring gas inlet or passage 31, while the threading of said air-nozzle outwardly 125 will cause said gas inlet or passage to be enlarged.

The gas enters the annular gas chamber 32 within said hollow head or enlargement from the gas inlet pipe, which may have a suitable valve therein to regulate or entirely 5 shut off the supply of gas, and from this chamber the gas escapes through the space 35 between flanges 20 and 30 and passes through the annular inwardly-flared gas inlet or passage 31 in the form of a circular stream toward a common point within the 10 mixing chamber indicated at 39.

The air passes into the air-nozzle from the air inlet pipe 22, which may also have a valve therein, and is directed through the inwardly-flaring annular air passage between the inner portion of the wall of said air-nozzle and the air deflecting cone, and the annular body of air thus supplied intersects the inrushing annular body of gas, preventing the gas from 20 passing directly along the lines indicated at 40 and meeting at said common point 39, the gas and air thus entering the mixing chamber in intersecting lines and in streams of annular formation, thoroughly commingle within 25 the mixing chamber and continue through said mixing chamber, while disturbed in their respective courses, so that a thorough commingling of gas and air takes place. The resultant mixture passes out as a combustible 30 product through the mixture outlet pipe 16. The intersecting of the annular stream of gas by the annular stream of air issuing from the air-nozzle deflects the annular stream of gas from its course toward the common center 39 35 and causes a whirling action within the mixing chamber, with the result that a thorough commingling of gas and air takes place throughout the length of the mixing chamber, and it will be noted that this mixing chamber 40 is devoid of internal walls or other obstructions, so that a free passage for the gas and air is assured. The pressure of the gas entering said mixing chamber is increased before it reaches the point of consumption, 45 by reason of the gas passing through the reducer cap or concentrator 9 and escaping at the restricted portion of said cap or concentrator through the mixture outlet pipe 16.

In the construction shown in Figs. 1 to 4, 50 adjustment is provided only for the admission of gas into the mixing chamber; but in the modification shown in Figs. 5 and 6, I have provided an adjustable air-deflector in connection with the adjustable air-nozzle, 55 and in this construction the air-nozzle is provided with a cross bar 41 and the air-deflecting cone 36 has a threaded supporting stem 42 extending outwardly from its apex, said stem being threaded through a threaded 60 axial opening in said cross bar. By rotating said stem, the cone is moved outwardly or inwardly, as may be desired, to decrease or increase the width of the annular flaring air passage 37 between said cone and the surrounding portion of the wall of said air 65

mixer. In this manner the air can be adjusted in proper proportion to the gas admitted into the mixing chamber.

Having thus described my invention, what I claim is:—

1. A gas mixer, comprising a mixing chamber having an outlet at one end, a hollow head at its other end, and an internal flange at the junction of said hollow head and mixing chamber having its inner peripheral wall tapered inwardly toward said mixing chamber, an air nozzle axially adjustable in said hollow head and having an externally-tapered portion and an internal flaring portion at its inner end, the surface of said externally-tapered portion being parallel with the inwardly-tapered wall of said internal flange and being spaced therefrom to form an annular inwardly-tapered inlet, a gas inlet pipe opening into said hollow head, and a cone within said air nozzle spaced from the internally flared portion thereof and forming between the two an annular inwardly-flared air passage through which an annular film or body of air is adapted to pass to intersect an annular film or body of gas at said annular gas inlet traveling into said mixing chamber.

2. A gas mixer comprising a casing having an end wall provided with a threaded opening, an annular grease groove formed in said threaded opening, a grease duct extending outwardly from said grease groove, means for delivering grease through said duct into said groove, and an air nozzle threaded into said opening and extending inwardly beyond said flange, said air nozzle serving to close said grease groove, an air deflecting cone positioned axially in said air nozzle at its inner end and spaced from the wall of said nozzle, and an internal flange formed at the junction of said mixing chamber and said hollow head and extending partly into said head and surrounding the inner end of said air nozzle, said internal flange having its inner peripheral wall tapered toward the interior of said mixing chamber and said air nozzle having its exterior tapered inwardly parallel with the tapered wall of said internal flange and spaced from the latter to form an annular inwardly-tapered gas inlet, and a gas inlet pipe connected to said hollow head.

3. A gas mixer, comprising an elongated chamber having an outlet at one end and an inlet axially disposed at its other end provided with an inwardly-tapered wall, a nozzle adjustably retained with its inner end partly entered into said inlet and having its exterior surface at its inner end tapered inwardly to conform to the tapered wall of said inlet, said tapered inner end being spaced from said tapered wall to form an annular inlet between the two, said nozzle having an inwardly-flared internal portion at its inner end, and a cone fitted into the inner end of

said nozzle and spaced from the wall of said inwardly-flared internal portion to form a second annular inlet between the two, means to supply gas to all points of one of said 5 annular inlets, and means to supply air to all points of the other annular inlet so as to intersect the entering gas at its annular inlet.

4. A gas mixer, comprising an elongated cylindrical mixing chamber having an outlet at one end and a hollow head at its other end provided with a threaded axial opening in its end wall, said mixer having an internal flange on its wall at the junction of said mixing chamber with said hollow head, said 10 internal flange extending into said mixing chamber and into said hollow head and having its inner peripheral wall tapered inwardly toward the interior of said mixing chamber, an air nozzle threaded into the outer 15 wall of said hollow head and extending partly into said internal flange and being spaced therefrom, said internal flange and air nozzle forming an annular gas chamber within said hollow head connected with said mixing 20 chamber through the medium of the space between said flange and said air nozzle, an air inlet pipe connected to said air nozzle, a gas inlet pipe connected to said hollow head, and a cone axially disposed within the air nozzle 25 at the inner end thereof and spaced from the surrounding portion of the wall of said air nozzle to form an inwardly-flaring air passage at the inner end of said nozzle.

5. A gas mixer, comprising a mixing 30 chamber having an axial opening at one end provided with an inwardly-tapered inner peripheral wall, and an outlet spaced from said axial opening, an air nozzle having an externally-tapered portion at its inner end spaced 35 from the inwardly-tapered wall of said axial opening to form an annular inwardly-tapered gas passage, said air nozzle having an air inlet, a cylindrical interior portion adjacent 40 said air inlet, an inwardly-flared portion adjacent said cylindrical interior, and a second inwardly-flared portion extending from said 45 first-mentioned inwardly-flared portion to the inner extremity of said nozzle, said second-mentioned inwardly-flared portion being 50 at a greater angle than said first-mentioned inwardly-flared portion and meeting the externally-tapered portion of said air nozzle at a sharp angle, and a cone disposed within said flared portions and extending into 55 the cylindrical portion of said air nozzle, said cone having its wall spaced from the walls of said inwardly-flared portions to form an annular air passage through which air is passed and intersects the gas passing 60 through said annular inwardly-tapered gas passage.

6. A gas mixer having an annular inwardly-tapered gas passage and an outlet spaced 65 from said gas passage, an air nozzle having a portion thereof forming one wall of said gas

passage and having an axial air opening, a diametral bar disposed in said air nozzle, and a cone positioned within the inner end of said air nozzle and having a threaded stem extending from its apex and threaded through said diametral bar, said cone being spaced from the wall of said air nozzle to form an annular inwardly-flared air passage and said threaded stem being adjustable in said diametral bar to cause the cone to be moved inwardly or outwardly to enlarge or diminish said annular inwardly-flared air passage.

In testimony whereof I affix my signature.
